BOTTLE FILLER AND CAPPER APPARATUS

Carl A. Namur and Charles M. Anderson, Kenosha, Wis., assignors to Specialty Brass Company, Kenosha, Wis., a corporation of Wisconsin

Application November 4, 1936, Serial No. 109,162

6 Claims. (Cl. 226—76)

This invention relates to apparatus for use in filling and capping bottles and other containers, and involves particularly a type of mechanism suitable for controlling the movement of bottles as they are being filled and capped. The invention is especially adapted for use in connection with the filling and capping of milk bottles, but may be used in other connections.

An object of the invention is to provide rotary conveyor mechanism in which the bottles may be supported and conveyed in interrupted rotation as they are being filled and capped.

Another object is to provide mechanism by which the bottles may be rotated and raised at certain intervals in their rotation to make successive contact with filler and capper mechanisms.

A further object is to provide conveyor mechanism which may be easily adapted to accommodate bottles or containers of different heights and sizes. Other objects and advantages will appear as the specification proceeds.

A preferred embodiment of the invention is illustrated in the accompanying drawings in which—

Fig. 1 is a view in front elevation of the device; Fig. 2, a view partly in section of the conveyor mechanism and the supporting platform, the section being taken as indicated at line 2 of Fig. 1; Fig. 3, a plan view of the table and its mounting, line 2 of this figure indicating the plane of the section in Fig. 2; Fig. 4, a fragmentary view showing in section the position of the table and pin when adjusted for medium sized bottles, the section being taken as indicated at line 4 of Fig. 3; and Fig. 5, a fragmentary view similar to Fig. 4, but showing the table and pin after adjustment to accommodate small sized bottles, the section being taken as indicated at line 5 of Fig. 3.

As illustrated, A designates a frame; B, a cam member; C, a table and means for mounting same; and D, gear mechanism for rotating table C.

The frame A may be of any suitable construction. In the embodiment illustrated it includes a platform 10 resting on three legs 11. Extending upwardly from platform 10 are the standards 12, 13, and 14. The standard 14 is closely associated with the features of the invention and will be described later in greater detail. A tank 40 is supported upon the standards 12, 13, and 14, and may contain the liquid with which the bottles are to be filled.

Attached to tank 40 are the two sets of filler tubes 41 for dispensing the liquid into the bottles. These tubes are of well known construc-

tion and it need only be said here that they are equipped with suitable springs and valves to dispense the liquid as the top of a bottle is pressed up against one of them. In the present embodiment four tubes are used, but any number of tubes may be used.

Suitable capping mechanism 42 is also attached to tank 40 and is of construction well known to the trade. It is sufficient to say that this mechanism is arranged to place caps on the bottles as they are pressed up against it. In this embodiment the capping mechanism caps two bottles simultaneously. This mechanism should be so mounted as to be arcuately aligned with filler tubes 41.

The standard 14 is of tubular form and may be secured to platform 10 by the use of screws 15. Slots 16 extend through its walls at its lower portion. It is reinforced at 17 and provides a bearing 18 which extends transversely of slots 16. 20

Mounted in bearing 18 is the shaft 19 to which is secured the cam member B which is adapted to rotate within slot 16. Member B is of the general shape as illustrated and is shown more clearly in Fig. 1 of the drawings. The peculiar shape shown has been found to be particularly desirable for use in connection with the bottle filling and capping mechanisms in common use. It may be seen that the larger radii of the cam are uniform between points 20 and 21, so that 30 the top surface of the cam remains at its highest level during one interval in its rotation.

Above cam member B and within standard 14 is a plunger rod 22 which is equipped at its lower end with a roller 23 which is adapted to contact the top surface of cam member B. At its top end rod 22 is equipped with a transverse pin 24 which extends through slots 25 in the walls of standard 14. The ends of pin 24 are provided with rollers 26 for supporting the rotatable 40 sleeve 27.

Sleeve 27 has at its upper end an in-turned flange 28 which rests upon rollers 26. At its lower end is an outwardly-turned flange 29. Table C is received over sleeve 27 and in its lower 45 position rests against flange 29.

Table C may be of any suitable construction. In the embodiment illustrated sockets 30 having drain holes 30a are provided for the accommodation of eight quart sized milk bottles. The 50 number and size of the sockets, however, may be varied as desired. Adjacent the hub of table C is an aperture 31 through which pin 32 extends when the table is in its lower position. Pin 32 is secured in flange 29 and when engaged with 55

table C rotatably secures the table with sleeve 27. Also adjacent the hub of table C and angularly displaced from aperture 31 is a boss 33 more clearly shown in Figs. 3 and 4 containing bore 34 for receiving the top portion of pin 32. Another bore 35 capable of receiving the top of pin 32 is located in the bottom of table C and is angularly displaced from bore 34. The relative position of the parts when pin 32 is in bore 35 10 is more clearly shown by Fig. 5.

The gear means for rotating table C comprises a mutilated gear 36 which is mounted about standard 14 and is equipped with an upper tubular extension 36a, the walls of which are disposed between standard 14 and sleeve 27. Gear 36 has teeth 37 which are discontinued at four places so as to provide four toothed sections. In gear 36 is an aperture 38 which receives the lower extension 39 of pin 32 to secure the gear 15 against rotation with respect to table C.

Another mutilated gear 43 is mounted on shaft 19 to which cam member B is secured, and is in engagement with gear 36. Unlike gear 36, gear 43 has only one toothed section. The toothed 20 section of gear 43 is adapted to mesh with either toothed section of gear 36. The end tooth of gear 43 which is first to make engagement with the teeth of gear 36 and designated in the drawings by character 44, may be formed of rubber or other resilient material if so desired. Such construction has been found to aid in eliminating the shock of first engagement.

An electric motor 45, mounted on platform 10, is here provided for actuating the various parts 35 of the device, though any source of power suitable for such a purpose might be utilized.

The shaft 46, leading from motor 45, is connected to gear 43 through a safety clutch arrangement shown more clearly in Fig. 2. The 40 shaft 46 is secured to a toothed wheel 47 by means of clamps 48. Wheel 47 contains a central bore which receives the reduced end portion 49 of shaft 19. The teeth on wheel 47 are engaged by dog 50 which is pressed by spring 51 into engagement with the teeth of the wheel. The screw 52 which holds dog 50 and spring 51 within bore 53 of gear 43 may be removed and the clutch 45 left to run free when so desired.

To operate the device an operator may put an 50 empty bottle in one of recesses 39 in table C and start the electric motor. The motor shaft 46 will turn in counterclockwise direction and through connection of wheel 47 with dog 50 will turn gear 43 in counterclockwise direction. At 55 every revolution of gear 43 the toothed section of this gear will engage one of the toothed sections of gear 36 to turn that gear one quarter turn. Table C, being rotatably secured to gear 36, is also turned one quarter revolution.

Gear 43, being secured to shaft 19, also rotates 60 the shaft and cam member B. The relation between cam B and gears 36 and 43 is such that the cam operates to raise plunger 22 and consequently table C during the interval the teeth of 65 the gears are not in engagement, so the cam operates to raise the table C during the intervals when it is not in motion.

The table C rotates one quarter revolution at 70 a movement and is so arranged that the empty bottle which has been placed on the table will be stopped immediately under one of filler tubes 41. Then, during the interval the table is not in motion, the cam B operates to raise plunger 22 which causes the sleeve 27 and table C to be raised. The top of the bottle impinges the filler 75

tube and through compression of a spring a valve is opened which allows milk or other liquid to be discharged into the bottle at a rather fast rate. The bottle is not entirely filled at this position, however, and the cam continues its motion allowing the plunger and table to descend again to their original positions.

When the toothed section of gear 43 makes engagement with the succeeding section on gear 36, this causes table C again to rotate through 10 a quarter revolution. This brings the bottle, now partly filled, immediately under another of filler tube 41. The cam B again operates to raise the table and the top of the bottle impinges the filler tube and is this time completely filled. The 15 cam B then turns to allow the table to again descend to its original position.

Upon another quarter revolution of the table the bottle is moved to a position directly under a capping mechanism. Here, as the table is again 20 raised, a cap is placed upon the bottle. After still another quarter revolution of the table the filled and capped bottle comes to its starting position where it may be removed and replaced with an empty bottle.

In the above explanation of operation one bottle has been followed through succeeding steps, but as the machine is operated these steps may take place concurrently upon different bottles. Two bottles are being partly filled, two bottles are 30 being completely filled, and two bottles are being capped as table C is being raised but once.

If smaller bottles are to be filled the table may be adjusted to accommodate the smaller bottles. This is accomplished by raising table 35 C until pin 32 is removed from aperture 31, then turning the table until pin 32 is over boss 33, and then allowing the pin to enter the bore 34, which position is clearly shown in Fig. 4 of the drawings. This raises the table to the height as 40 shown in the lower set of dotted lines in Fig. 1.

If still smaller bottles are desired to be used, the table may again be lifted to disengage pin 32 from boss 33, and the table turned so that pin 32 will engage bore 35. This represents the 45 position shown in the upper set of dotted lines in Fig. 1.

Should anything go wrong in the operation of the device so as to block the movement of the table, the dog 50 will disengage from the teeth 50 of wheel 47 and will allow the shaft 46 to rotate without causing rotation of gears 43 and 36. Thus, the table rotating mechanism of the machine will be stopped if it should become jammed, and will not break any of its parts.

Several advantages are gained by providing two sets of filler tubes for filling the bottles in two steps. For one thing, the filling operation takes a longer time than does the capping operation, and by the bottles being filled at two stages simultaneously greater speed is accomplished. Perhaps a greater advantage lies in giving the foam or bubbles which appear after the first rapid discharge a chance to disappear before the 60 bottle is finally filled. Otherwise the foam would cause the milk or other liquid to overflow before the bottle is completely full.

Another advantage lies in the ease with which this machine is operated. As two pairs of bottles 70 are being filled and one pair is being capped, the operator is removing the remaining pair of bottles, now filled, and replacing these with empty bottles. The operator need not move from place to place in starting and removing bottles, nor 75

does he need to wait for successive steps in the operation to take place.

While we have shown gear 36 provided with four toothed sections, it will be understood that these sections will vary in number and extent as required, by the size and capacity of the machine.

While we have described a specific structure it must be understood that many changes may be made without departing from the spirit of our invention. The foregoing detailed description has been given for clearness of understanding only, and no unnecessary limitations should be understood therefrom, but the appended claims should be construed as broadly as permissible, 15 in view of the prior art.

We claim:

1. In a device of the character set forth, a frame including an upright standard, a table rotatable about said standard and adapted to 20 carry containers thereon, mechanism for intermittently rotating said table, said mechanism including a gear rotatably mounted on said standard and adapted to remain in fixed vertical position and including also means for connecting 25 said gear in rotational relation with said table, and means for intermittently raising and lowering said table.

2. In a device of the character set forth, a frame including an upright tubular standard, a 30 shaft journaled in said frame and equipped with a cam, a plunger within said standard and resting upon said cam so as to be raised and lowered as said shaft is rotated, a table rotatable about said standard and movable vertically of said 35 standard, means connecting said plunger and table for raising said table when said plunger is raised, a gear rotatably mounted about said standard and in drive relation with said table, said gear being adapted to remain in fixed vertical position 40 on said standard, and means for intermittently rotating said gear whereby said table is given intermittent rotational movement.

3. In a device of the character set forth, a frame including an upright tubular standard, a 45 shaft journaled in said frame and equipped with a cam, a plunger resting on said cam and extending upwardly within said standard, a table rotatably carried by said plunger and adapted to move vertically of said standard upon actuation of 50 said plunger by said cam, a mutilated gear in

fixed vertical position in said frame and adapted to rotate about a substantially vertical axis, said gear being in drive relation with said table, a second mutilated gear driven by said shaft and in engagement with said first mentioned gear, and means for continuously rotating said shaft. 5

4. In a device of the character set forth, a frame including an upright tubular standard, a shaft journaled in said frame and equipped with a cam, a plunger resting on said cam and extending upwardly within said standard, said plunger being adapted to reciprocate vertically as said shaft is rotated, a table rotatably supported on said plunger and adapted to move vertically with said plunger, a mutilated gear rotatable about a 10 vertical axis and in drive connection with said table, drive means for actuating said gear to produce intermittent rotation of said table, clutch means for enabling release of said drive means, said drive means including a second mutilated 15 gear normally in drive relation with said shaft, said clutch means including a toothed gear secure upon said shaft, and a spring-pressed plunger in said second gear, said plunger being in resilient engagement with said toothed gear. 20 25

5. In a device of the character set forth, a frame including an upright tubular standard, a shaft journaled in said frame and equipped with a cam, a plunger extending within said standard and resting upon said cam so as to be raised 30 and lowered as said shaft is rotated, a table rotatable about said standard and movable vertically of said standard, said table being equipped with a table-carrying member by which the table is carried at different relative levels, a gear rotatably mounted about said standard, a pin extending through said gear and into said table for connecting said table and gear in drive relation, and means for intermittently rotating said gear whereby said table is given an intermittent 35 40 rotational movement.

6. Apparatus as set forth in claim 5 in which said table is equipped with at least two sockets and in which said pin is adapted to engage one of said sockets to maintain said table at one of said relative levels and to engage the other of said sockets to maintain said table at another of said relative levels. 45
